UNITED STATES PATENT OFFICE.

RICHARD I. CARWALHO, OF OTTUMWA, IOWA.

MILK-BOTTLE HOLDER.

1,282,753.

Specification of Letters Patent. Patented Oct. 29, 1918.

Application filed April 3, 1918. Serial No. 226,455.

To all whom it may concern:

Be it known that I, RICHARD I. CARWALHO, a citizen of United States, residing at Ottumwa, in the county of Wapello and State 5 of Iowa, have invented new and useful Improvements in Milk-Bottle Holders, of which the following is a specification.

This invention relates to a milk bottle holder and the object is to provide a device which may readily be attached to a door frame, window frame, or any other suitable portion of a building, and which is designed to receive and support a milk bottle in such position that it will not readily be broken through accident and will be 10 out of the way of dogs, cats, or other animals.

A further object is to provide a device adapted to receive empty bottles, as well as 20 bottles containing milk, after the empty bottles have been removed, and a device to which the milk tickets may readily be attached, or which will receive such tickets in any suitable manner.

25 A still further object is to provide an inexpensive device which cannot readily be displaced and which will not get out of order, and which shall consist in the preferred form of a single element of sheet 30 metal pressed into the required form and serving as means for mounting a spring held member designed to retain the bottle in position, and to permit the removal thereof by a slight lateral pressure as the 35 bottle is picked up by the dealer or by the customer.

With the foregoing and other objects in view the invention consists in the novel construction, combination, and arrangement 40 of elements hereinafter described and claimed.

In carrying out my invention I provide a bracket comprising a member formed of sheet metal, and having a cutaway portion 45 adapted to receive the neck of the bottle. This bracket includes a main portion 10 provided with an opening 12 having a curved inner portion 14, the curved portion merging into straight edge portions 15 and

16. The bracket includes a deflected end 50 portion 18, and deflected portions 19 and 20 at the sides. Each of the deflected elements is apertured for the accommodation of screws or other securing devices by means of which the bracket is attached to 55 a door frame or window frame.

The engaging device comprises a pivotally mounted member designated 21 operating on a pivot 22, this member having a rounded portion 23 normally projecting beyond one straight edge of the opening above mentioned. The pivoted engaging device is provided with a deflected portion 24 apertured at 25 for the accommodation of a transversely extending bar 26 having its 60 ends mounted in the deflected side portions of the bracket. The bar is encircled by coil spring 28 bearing against the deflected portion of the pivoted engaging device and normally retaining the curved outer end of 65 said engaging device in position for holding a bottle which has been forced inwardly through the straight edge portions of the opening until the neck of the bottle is in 70 approximate contact with the inner curved 75 edge of the opening. The engaging device, being retracted during the operation of inserting the bottle, assumes a locking position after the bottle is properly positioned in the bracket. 80

The device may be mounted at any suitable distance above a door step or a sill of a window, in order that the bottle may be accessible, and yet be in a safe position. Not only will many bottles be saved which 85 would otherwise be broken, but the filled bottles reach the customer in a more sanitary condition.

What is claimed is:

In a device of the class described, a 90 bracket having flanges extending around three sides thereof, the main portion of the bracket comprising a plate having a cutaway portion opening toward a fourth side of the bracket, said flanges projecting upwardly from the plate, the cutaway portion being adapted to receive the neck of a 95 bottle the upper portion of which is pro-

tected by the flanges, a pivoted arm projecting beyond the edge of the cutaway portion at one point, said arm having a rounded end, an offset projecting upwardly from the opposite end of the arm, a rod extending transversely of the plate and between two of the flanges, said rod passing through

the offset portion of the arm, and a spring encircling the rod and bearing against the offset portion and the flange at one side of 10 the bracket.

In testimony whereof I affix my signature.

RICHARD I. CARWALHO.
